UNITED STATES PATENT OFFICE.

CLIFFORD DAILEY, OF NEW YORK, N. Y.

DESIGN FOR A LOCKET.

42,730.

Specification for Design.

Patented July 9, 1912.

Application filed May 1, 1912. Serial No. 694,585. Term of patent 7 years.

To all whom it may concern:

Be it known that I, CLIFFORD DAILEY, a citizen of the United States, and a resident of the city of New York, borough of Brooklyn, in the county of Kings and State of New York, have invented a new, original, and ornamental Design for Lockets, of which the following is a specification, reference being had to the accompanying drawing, in which—

Figure 1 is a perspective view of the ob-

verse side of my locket in open position; and Fig. 2 is a similar view of the reverse side.

I claim—

The ornamental design for a locket as shown.

CLIFFORD DAILEY.
